UNITED STATES PATENT OFFICE.

MORRIS L. GOLDBERG, OF BROOKLYN, NEW YORK.

DESIGN FOR A MASSAGING BRUSH.

Application filed April 12, 1922. Serial No. 1,697. Term of patent 14 years.

To all whom it may concern:

Be it known that I, MORRIS L. GOLDBERG, a citizen of the United States, residing in the city of New York, borough of Brooklyn, county of Kings, and State of New York, have invented a new, original, and ornamental Design for Massaging Brushes, of which the following is a specification, reference being had to the accompanying drawings, forming a part thereof, and of which

Figure 1 is a plan view of one side, Fig. 2 is an edge view, and Fig. 3 is a plan view of the opposite side of the brush illustrated in Fig. 1, illustrating a massaging brush, showing my new design.

I claim:

The ornamental design for a massaging brush, substantially as shown.

MORRIS L. GOLDBERG.
